UNITED STATES PATENT OFFICE.

ARTHUR E. JONES, OF SYRACUSE, NEW YORK, ASSIGNOR TO THE O. M. EDWARDS COMPANY, INC., OF SYRACUSE, NEW YORK, A CORPORATION OF NEW YORK.

SHEET-METAL DESK CONSTRUCTION.

1,287,038.

Specification of Letters Patent. Patented Dec. 10, 1918.

Application filed December 8, 1913. Serial No. 805,391.

To all whom it may concern:

Be it known that I, ARTHUR E. JONES, a citizen of the United States, and a resident of Syracuse, in the county of Onondaga and 5 State of New York, have invented a certain new and useful Sheet-Metal Desk Construction, of which the following is a specification.

This invention relates to sheet metal furniture and has for its object the production 10 of a desk construction, and it consists in the novel features of construction herein-after set forth and claimed.

In describing this invention, reference is 15 had to the accompanying drawings, in which like characters designate corresponding parts in all the views.

Figure 1 is a vertical cross-sectional view 20 of the desk showing the end plate in inner elevation.

Figs. 2 and 3 are vertical sectional views on lines A—A and B—B, Fig. 1.

Fig. 4 is a horizontal sectional view on line C—C, Fig. 1.

25 Fig. 5 is an enlarged fragmentary inner face view of the opposing ends of the top bar and front post of the end plate and contiguous parts.

Fig. 6 is an enlarged cross-sectional view 30 through the top bar, the contiguous portion of the end plate and the facing plate being also shown.

Fig. 7 is a detail fragmentary view illustrating the manner of attaching the back 35 plate in position.

Fig. 8 is a cross-sectional view through the front post of the end plate.

This sheet metal desk construction comprises, generally, an end plate having its 40 front and rear margins bent to form hollow posts projecting outwardly so that the body of the plate is inset or depressed, a top bar extending along the upper margin of the greater portion of the plate and having a downturned end meeting the front post and forming a continuation thereof and meeting at its rear end the forwardly projecting bead or rail which forms a continuation of the rear post, the top bar being formed with 45 a laterally facing channel for guiding the roller top of the desk.

The invention also includes constructions 50 for attaching the back plate in position and for attaching the drawer guides or ways in 55 position.

1 is the end plate having its front and rear margins bent to form angular hollow posts 2, 3, and having its lower margin bent to form a horizontal rail 4 and the rear portion of its upper margin bent to form 60 a forwardly projecting rail 5 which is an extension of the rear post 3, the outer faces of the posts 2, 3 and rails 4, 5 being flush and offset with respect to the surface of the body of the plate 1, so that the body of the 65 plate 1 is depressed or set in relatively to the posts and rails and forms a single large panel. The rear post is higher than the front post and the upper margin of the end plate extends downwardly from the upper 70 end of the front post.

6 is a bar extending along the front portion of the upper edge of the plate 1 and having its front end portion downturned and meeting at its end the upper end of 75 the post 2 and forming a continuation thereof, and having its rear end meeting the front end of the rail or bead 5, the rear end of the bar and the front end of the rail being mitered and welded together, as seen 80 in Fig. 1. The bar 6 forms a continuation of the front post 2 and the rail 5 and is formed with a channel 7 in its lower face for receiving the upper edge of the plate 1 and with a laterally facing channel 8 on its 85 inner side for receiving the margin of the roller top of the desk, not shown.

As seen in Fig. 5, the bar is secured to the post 2 by means of angular brackets 2^a and 6^a located in the post 2 and in the channel 7 of the bar at the upper end of the post and contiguous end of the bar, corresponding arms of the brackets 2^a, 6^a being secured to the post 2 and bar 6, respectively, by rivets 2^b, 6^b and the other arms of said 90 brackets lying against each other and being secured together by bolts 2^c. The portion of the bar 6 on the inner side of the front end thereof is cut away to form a slot 6^c through which the top plate of the desk 100 extends.

The bar 6 is secured to the margin of the plate 1 by suitable means as screws 9. 10 is a channel bar, the channel of which forms a continuation of the channel 8 of the bar 6, 105 the bar 10 having a horizontal portion aligned with the rear end of the bar 6 and secured as by welding thereto and the vertical portion extending downwardly along the back of the desk or along the rear post 3. 110

11 is an angle-iron strip secured to the inner face of the end plate and extending horizontally and rearwardly and having its upper face 11^a alined with the lower side 5 of the slot 6^c at the junction of the front post 2 and the lower end of the bar 6, the strip forming a support for the table plate 12 of the desk.

13 is a face plate opposed to the portion of 10 the end plate 1 above the strip 11 and secured, as by screws 14, to a lip 15 depending from the end side of the bar 6 beneath the channel 8 thereof, and at its lower edge being secured to one flange of the angle-iron 15 16 secured to upper face of the table 12.

17 is the back plate which is secured at each side margin to the rear post 3, the post 20 3 being formed with an inturned flange 17^a which is formed with a plurality of slots 17^b, and the back plate 17 being formed along each side margin with offset vertical tongues 18 which interlock with the slots 17^b, and by a downward movement carrying the tongue 25 downwardly into position to interlock in the slots.

19 are drawer guides in the form of channels which are secured in position in any suitable manner, and as here shown the drawer guides are formed with offset 30 tongues 20 at their front ends for entering behind flanges 21 of the front post 2, Fig. 4, and with lugs 22 at their rear ends arranged to enter in slots 23 in the vertical flange 24 of the angle iron strips 25 secured to the 35 inner face of the end plate 1 in the rear of, and spaced apart, form the post 2. Each lug 22 is arranged to enter its slot when the tongue is interlocked behind the flange 21, and the guide 19 is held in position by a key 40 26 passing through a perforation in the end of the lug 22.

A key 26 common to all the lugs 22 on the guides 19 contiguous to each end plate is used. The flange 21 of the front post 2 is 45 offset from the body of the end plate and the flange 24 of the angle iron strip 25 is also offset from the end plate, and these flanges 21, 24 are formed with additional flanges or lips 27, 28, arranged in planes at an angle to 50 the body of the end plate, which flanges are notched at 29, the notches extending to the bases of said lips or flanges; and the drawer guides are arranged in these notches with their backs thereof flatwise against the 55 flanges 21, 24 so that the offset tongues 20 may extend behind the flanges 21 and the lugs 22 will enter the slots 23 in the flanges 24.

30 are the legs of the desk which are 60 secured to extensions of the front and rear posts 2, 3, the extension 31 telescoping in the legs 30.

This desk is particularly advantageous in that the end pieces are of one piece of metal, 65 and further, owing to the arrangement of

the top channel pawl, a particularly simple and rigid construction is provided for with the minimum bending of the end plate.

What I claim is:—

1. A sheet metal desk construction comprising an end plate having its front and rear margins bent to form hollow posts, the rear post being higher than the front post whereby a portion of the upper margin of the plate extends downwardly toward the upper end of the front post, and a top bar 70 extending along the upper margin of the end plate and meeting the front post and forming a continuation thereof, the bar being formed with a laterally facing channel 75 on its inner side forming a guide for the roller top of the desk, substantially as and for the purpose described.

2. A sheet metal desk construction comprising an end plate having its front and rear margins bent to form hollow posts, the rear post being higher than the front post whereby a portion of the upper margin of the plate extends downwardly toward the upper end of the front post, and a top bar 80 extending along the upper margin of the end plate and being of substantially the same cross-sectional contour as the posts and meeting the front post and forming a continuation thereof, the bar being formed 85 with laterally facing channel on its inner side forming a guide for the roller top of the desk, substantially as and for the purpose described.

3. A sheet metal desk construction comprising an end plate having its front and rear margins bent to form hollow posts at the front and rear corners of the desk, the rear post being higher than the front post whereby a portion of the upper margin of the plate extends downwardly toward the upper end of the front post, and a bar 90 extending along the upper margin of the plate and having its front end portion curved downwardly and meeting the upper end of the front post and forming a continuation thereof, the bar being formed with a laterally facing channel on its inner side forming 95 a guide for the roller top of the desk, substantially as and for the purpose described.

4. A sheet metal desk construction comprising an end plate having its front and rear end margins bent to form hollow posts, and a portion of its upper margin bent to

form a hollow horizontal rail meeting the rear post and forming a continuation thereof, the rear post being higher than the front post whereby a portion of the upper margin of the plate extends downwardly toward the upper end of the front post, a bar 120 extending along the upper edge of the end plate and having its front end portion bent downwardly and meeting the front post and forming a continuation thereof and its rear 125 130

end meeting the top rail and being secured thereto to form a continuation thereof, the bar being formed with an inwardly facing channel on its inner side, substantially as and for the purpose set forth.

5. A sheet metal desk construction comprising an end plate having its front and rear end margins bent to form hollow posts, and a portion of its upper margin bent to 10 form a hollow horizontal rail meeting the rear post and forming a continuation thereof, the rear post being higher than the front post whereby a portion of the upper margin of the plate extends downwardly toward 15 the upper end of the front post, a bar extending along the upper edge of the end plate and having its front end bent downwardly and meeting the front post and forming a continuation thereof and its rear 20 end meeting the top rail and being secured thereto to form a continuation thereof, the bar being formed with a laterally facing channel on its inner side, and a channel bar arranged on the inner side of the end plate 25 and meeting the rear end of the first-mentioned bar beneath said rail and having its rear end portion turned downwardly along the rear post, the channel bar having its channel forming a continuation of the channel of the first-mentioned bar, substantially as and for the purpose described.

6. A sheet metal desk construction comprising an end plate having its front margin bent to form a hollow post, and its upper margin extending above the post and curving downwardly toward the same, a bar extending along the upper margin of the end plate and having a channel into which said margin extends, the front portion of 35 the bar curving downwardly and meeting the upper end of the post, and angular brackets located in the post and in the channel of said bar at the abutting ends of the post and bar, corresponding arms of the 40 brackets being secured to the post and bar respectively and the other arms thereof lying against each other and being secured together, substantially as and for the purpose specified.

50. 7. A sheet metal desk construction comprising an end plate having its front and rear end margins bent to form hollow posts, and a portion of its upper margin bent to 55 form a hollow horizontal rail meeting the rear post, the rear post being higher than the front post whereby a portion of the upper margin of the plate extends downwardly toward the upper end of the front post, a bar extending along the upper edge 60 of the end plate and having its front end portion bent downwardly and meeting the front post and forming a continuation thereof, and its rear end meeting the top rail and being secured thereto, the bar being 65 formed with a laterally facing channel on

its inner side, and portions of the abutting ends of the post and bar being separated on the inner side of the end plate forming a slot, a horizontally extending strip secured to the inner face of the end plate and having its upper face substantially aligned with the lower wall of said slot, and a plate supported by the strip, and extending through the slot, substantially as and for the purpose described.

70. 8. A sheet metal desk construction comprising an end plate having its front and rear end margins bent to form hollow posts, and a portion of its upper margin bent to form a hollow horizontal rail meeting the rear post, the rear post being higher than the front post whereby the portion of the upper margin of the plate extends downwardly toward the upper end of the front post, a bar extending along the upper edge 80 of the end plate and having its front end portion bent downwardly and meeting the front post and forming a continuation thereof and its rear end meeting the top rail and being secured thereto to form a 85 continuation thereof, the bar being formed with a laterally facing channel on its inner side, and portions of the abutting ends of the post and bar being separated on the inner side of the end plate forming a slot, a horizontally extending strip secured to the inner face of the end plate and having its upper face substantially aligned with the lower wall of said slot, a table plate supported at one end by said strip and extending through the slot, and a facing plate opposed to the upper portion of the end plate above the table plate and being secured to the channel bar and meeting the upper face 90 of the table plate, substantially as and for 95 the purpose specified.

9. A sheet metal desk construction comprising an end plate having its front and rear margins bent to form raised posts projecting outwardly from the body of the plate 100 and with raised outwardly extending beads or rails along its lower edge and along its upper edge from the rear post, whereby the body portion of the end plate is depressed below said post and rails, the upper bead terminating short of the front post, the rear post being higher than the front post whereby a portion of the upper margin of the plate extends downwardly toward the upper end of the front post, and a bar extending along the upper edge of the end plate and meeting the upper rail or bead 110 and having its front end downturned and meeting the front post, the bar forming a continuation of the front post and the bar being formed with a channel on its inner side, substantially as and for the purpose set forth.

10. A sheet metal desk construction comprising an end plate having its front and 120

- rear margins bent to form raised posts projecting outwardly from the body of the plate and with raised outwardly extending beads or rails along its lower edge and along 5 its upper edge from the rear post, whereby the body portion of the end plate is depressed, the upper rail terminating short of the front post, the rear post being higher than the front post whereby a portion of 10 the upper margin of the plate extends downwardly toward the upper end of the front post, and a bar extending along the upper edge of the end plate and meeting the upper rail or bead and having its front end down- 15 turned and meeting the front post, the bar forming a continuation of the front post and the upper bead or rail and being formed with a channel on its inner side, and portions of the abutting ends of the post and 20 bar being separated on the inner side of the end plate forming a slot, the end plate having a supporting strip extending horizontally and having its upper face alined with the lower side of the slot, and a table plate resting on said strip and extending through 25 the slot, substantially as and for the purpose described.
11. A sheet metal desk construction comprising an end plate and a curved bar extending along the upper margin of the end 30 plate and formed with a channel in its lower side for receiving the upper edge of the end plate and being formed with a laterally fac- 35 ing channel on its side which forms a guide for the roller top of the desk, substantially as and for the purpose specified.
- In testimony whereof, I have hereunto signed my name in the presence of two at- 40 testing witnesses, at Syracuse, in the county of Onondaga, in the State of New York, this 4th day of December, 1913.

ARTHUR E. JONES.
